UNITED STATES PATENT OFFICE.

HAROLD BROWN, OF KANSAS CITY, KANSAS.

DESIGN FOR PAPER WEIGHT.

Application filed June 5, 1924. Serial No. 9,806. Term of patent 3½ years.

To all whom it may concern:

Be it known that I, HAROLD BROWN, a citizen of the United States, residing at Kansas City, in the county of Wyandotte and State of Kansas, have invented a new, original, and ornamental Design for Paper Weight, as shown in the accompanying drawing and described in the following specification.

Figure 1 is an elevation of a paper weight. Figure 2 is a top plan view of the same.

I claim:

The ornamental design for paper weight as shown.

HAROLD BROWN.
